[57] CLAIM

The ornamental design for a wireless telephone system base unit or the like, as shown and described.

DESCRIPTION

FIG. 1 is a top, front and side perspective view of a wireless telephone system base unit or the like showing my new design;

FIG. 2 is a front elevation thereof;

FIG. 3 is a rear elevation thereof;

FIG. 4 is a left side elevational view thereof;

FIG. 5 is a top plan view, thereof; and

FIG. 6 is a right side elevation thereof.

The broken line showing of projections upon the upper face of the base unit is for illustrative purposes only.

FIG. 1

FIG. 2

FIG. 3

FIG. 4
